UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

LOADING APPARATUS

Original application filed April 24, 1916, Serial No. 93,043. Divided and this application filed April 9, 1923. Serial No. 630,831.

This invention relates to loading apparatus particularly adapted for loading coal at the working face in a coal mine, and is a division of my copending application Serial No. 93,048, filed April 24, 1916, for an improvement in mining machines.

One of the objects of the present invention is the provision of improved gathering mechanism which is adapted to move along a mine floor near the base of the mine wall to gather coal which has been dislodged from the working face.

A further object of the invention is the provision of improved gathering mechanism comprising a beveled nose piece in position to move along the floor and wedge itself under the coal to be loaded and prevent the gathering mechanism from riding up on the coal.

20 A further object of the invention is the provision of loading apparatus of improved construction and more efficient and economical in operation than loading devices previously devised.

25 Other objects of the invention will appear
herinafter, the novel features and combina-
tions being set forth in the appended claims.

Referring to the accompanying drawings
Figs. 1 and 2 taken together constitute a
30 complete top plan view of the machine
shown in operative position in a mine cham-
ber.

Figs. 3 and 4 taken together constitute a side elevation of the machine shown in Figs. 1, 2, 10.

35 1 and 2.
Figs. 5 and 6 taken together constitute a longitudinal vertical sectional view of the machine shown in Figs. 1 to 4, inclusive.

Fig. 7 is a vertical sectional view on line 40 7-7 of Fig. 6.

Fig. 8 is a vertical sectional view substantially on line 8—8 of Fig. 3, looking forward in the direction of the arrows.

Fig. 9 is a top plan view of the main base plate of the machine.

Fig. 10 is a bottom plan view of the movable scoop and conveyor forming a part of the loading machine; and

Fig. 11 is a top plan view of the construction shown in Fig. 10.

In the drawings the main base plate 20 is shown in position to support the greater part of the loading mechanism. This base plate is shown in the drawings so as to be

adapted to rest on and slide over a mine floor. 55
This base plate is provided with up-turned flanges 21 extending longitudinally along the edges thereof, for the purpose of strengthening the base plate, as shown in Figs. 8 and 9. The central portion of the base plate 20 is provided with a somewhat extended flat supporting surface 22, on which parts of the machine to be described slidably rest. This supporting surface 22 is shown in plan view in Fig. 9. 60 65

The base plate 20 as shown in Fig. 9 is provided at its forward end with an extension 23 having an upright standard 24 projecting upwardly therefrom and secured to the plate by cap screws 25, as shown in Fig. 70. The standard 24 carries a pair of pivot bolts 26 and 27, which project from the standard at opposite sides thereof to form pivotal supports for the swinging arms 28 and 29, there being a pair of arms 28 supported on the lower bolt 26 and a second pair of arms 29 supported on the upper bolt 27. The arms 28 and 29 are pivoted at the forward ends on pivot bolts 30 and 31, respectively, which are carried by a link 32 extending between the pivot bolts 30 and 31 and holding the latter in fixed relation to one another. By this construction, a vertically swinging arm is provided which constitutes a parallel motion device arranged to hold the link 32 in a vertical position regardless of the angle of the pair of swinging arms. Although this structure constitutes 75 80 85 90

part of the mining mechanism shown in Fig. 5, reference is made thereto herein to show that this mining mechanism is detachable at the pivots 26 and 27 so that the remaining mechanism may be used as a simple loading machine to gather and load coal which has been dislodged from the mine wall by another mining machine or by means of blasting operations. Reference is also made to the mining mechanism herein to illustrate a method of dislodging the coal by means of a separate machine such as that disclosed and covered in my copending application Serial No. 93,048, filed originally April 24, 1916.

The arms 28 are connected near the pivot 26 by a plate 33 as shown in Fig. 5, this plate 33 being secured to the inner side of each arm by means of cap screws 34. The plate 33 constitutes a platform on which a

motor 35 is mounted, connected by a worm and worm wheel enclosed in a casing 36 with a shaft 37 mounted on journals carried by the arms 28. The shaft 37 has secured thereto a pair of pinions 39, which mesh with the teeth of arcuate racks 40 secured to the forward end of base plate 23 and projecting upwardly therefrom as shown in Fig. 5. The operation of the motor 35 will drive the pinions 39 and thus swing the arms 28 and 29 upwardly or downwardly about their pivots 26 and 27, the direction of the pivotal movement of the arms 28 and 29 depending upon the direction of rotation of the motor 35. The motor 35 is governed by one of a series of controllers 41, shown in Fig. 1, which controllers are connected with the various motors for driving the different parts of the machine and are arranged to govern the speed and direction of the motor which they control.

The cutter head for dislodging the material from the mine vein is carried by the link 32, as shown in Fig. 3. Projecting forwardly in a horizontal direction on a line with the lower portion of the arm 28 is a supporting bracket 42, which is extended laterally to form a circular rack 43 which is rigid with the bracket 42. At the center of the rack 43 the bracket 42 is provided with a journal bearing for the yoke frame 46. The upper portion of this yoke frame 46 is provided with a journal bearing in the upper horizontal frame 55. Suitable gearing may be provided in the casing 60 for securing a slow feeding movement of the chain cutter 52, and gearing may be connected to the arcuate rack 43 to secure a quick-restoring movement of the core cutter.

A motor 49 is mounted on the yoke frame 46 in position to operate gearing in the casing 69 connected to a sprocket pivoted at 67 as shown in Fig. 3. A chain cutter 71 is guided around the cutter frame having the lower run 50, vertical run 73 and the upper horizontal run 52. This cutter frame is supported by the vertical cross-piece 51, which is secured to the yoke frame 46. An operating lever 89 is pivoted to the upper portion 53 of the yoke frame 46, so as to control the feeding mechanism which swings the core cutter on a vertical axis during the cutting operation.

Referring to Fig. 1, it will be seen that the rotation of the core cutter about its vertical axis 56 will form a crescent-shaped section of material in the mine vein. Fig. 5 illustrates that a number of cuts may be taken one above the other for each position of the entire machine, the upper and lower cores always being formed in horizontal planes regardless of the height to which the cutter head is adjusted by the arms 28 and 29. By this arrangement the chain cutter will dislodge the coal from the floor and roof

of the mine in such a manner as to leave a perfectly plane, smooth surface at both top and bottom of the mine chamber and deliver all of the material from the floor and roof of the mine. This cutting operation is particularly useful at the floor to facilitate the forward movement of the gathering mechanism as hereinafter described.

In order to remove the material severed by the cutting mechanism illustrated or by means of a separate machine or by means of blasting, a conveyor is provided which may be moved into and out of position beneath the dislodged coal at the working face. This conveyor, shown in Fig. 1, consists of an endless chain 100 provided with outwardly extending flights 101 pivotally secured at their inner ends to lugs 102, which are located at intervals along the chain 100 by being attached to spaced links of the chain. The chain is mounted to travel on a movable bed plate 103, which is oblong in shape as shown in Fig. 1, and which is provided at opposite sides with runways for the forward and return runs of the conveyor flights 101.

The plate 103 as shown in Figs. 10 and 11, has a longitudinally extending slot 104 extending through the central portion thereof, and the chain is guided around this slot by upwardly extending guide flanges or shoulders 105, shown most clearly in Fig. 8. At the forward end of the run for the chain 100 an overhanging flange 105' projects from the shoulder 105 in position to extend over the chain 100 and hold the chain against upward movement relatively to the plate 103.

At one side of the plate 103 on the return run of the conveyor the shoulder 105 is continued upwardly to form a flange or guard wall 106, as shown in Figs. 1 and 8, to prevent material being carried by the conveyor from escaping from the inner edge of the bed plate. A similar wall 107 is provided at the outer edge of the conveyor plate or pan 103. At the side of the gathering plate 103 along which the conveyor flights 101 move forwardly toward the cutter head, the outer edge of the plate is provided with a peripheral flange 108, as shown in Fig. 8, which supports the outer edge of the cover plate 109 secured to the plate 103 and spaced above this plate a sufficient distance to permit the travel of the chain 100 and the flights 101 carried thereby, between the bed plate and the cover plate. This cover plate 109, as will be seen by referring to Fig. 1, forms a running board on which the operator may stand and along which he may walk in moving from one end of the machine to the other.

As shown in Fig. 10, which is a bottom plan view of the movable gathering plate shown in plan view in Fig. 11, the plate 103 is provided on its lower side with supporting slides or runs 110, which extend along the

edges of the opening of the slot 104 at the central portion of the plate. These slides 110 as shown in Fig. 8, rest upon guideways 111 formed on the projections 23 of the main base plate 20. This projection 23 is shown in longitudinal section in Fig. 5.

An upwardly extending flange 112 as shown in Fig. 8 is positioned along the inner edge of one of the guideways 111, while the 10 guard plate 113 extends upwardly at the inner edge of the other guideway 111. As the plate 103 is moved longitudinally on the base plate 20, in a manner to be described, it is guided in its movement by the flange 112 and by the upwardly extending plate 113. In other words, the slideways 110 shown in Fig. 10 rest on the guideways 111, and embrace the vertical walls of the flange 112 and guard plate 113.

20 The rear portion of the plate 103 as shown in Fig. 10, is provided with a bearing surface 114 which slides over the surface 22 as the plate 103 is moved along the base plate 20. It should be understood that Fig. 10 is 25 a bottom plan view, and therefore when the plate 103 is mounted on the base frame the surface 114 of Fig. 10 rests on and slides over the surface 22 of Fig. 9. A pair of shoes 115 is secured to the under surface of the plate 103 near the forward end of the latter, as shown in Fig. 10, in position to bear on the mine floor at opposite sides of the base plate 20. This is shown clearly in Fig. 8, which is a sectional view on the line 30 8—8 of Fig. 3 looking forwardly in the direction of the arrows.

The plate 103 carries at its forward end an arcuately shaped platform 116. This platform as shown in Fig. 5, is made comparatively thin but in conformity to suitable strength and is provided with a beveled edge 117 to form a recess in which the flights 101 travel and also to form a scoop for directing the material on to the platform 116. 40 By providing such a flat comparatively thin nose portion for the forward end of the conveyor pan 103 the beveled arcuate edge 117 will be in position to move along the floor and penetrate the mass of dislodged coal and 45 prevent the said nose piece from riding up on the coal which is to be loaded. In other words, by having the platform 116 comparatively thin and beveled at its forward end as shown at 117, any material resting on the 50 mine floor will be forced upwardly into the path of the conveyor flights. The wedging action of the beveled nose piece will keep the bottom of the platform 116 in engagement 55 with the floor. As shown in Fig. 5 the rear side of the bevel 117 is provided with a shoulder to act as an arcuate guard for the flights 101.

60 The platform 116 is preferably given the same radius of curvature as the radius of the cutter frame in order that its front edge

may fit closely with the cut formed by the loop core cutter. At the forward end of the running board 109 at the point where the conveyor mechanism passes from beneath the running board onto the platform 116, a 70 guide arm 119 is positioned for preventing coal from being moved backwardly onto the running board when the platform 116 with its beveled edge is moved forwardly.

As shown in Fig. 5, the bearing plate 114 which supports the rear end of the conveyor bed plate 103 is spaced downwardly from the plane of said bed plate and carried on downwardly extending flanges or walls 120. This gives the conveyor bed plate 103 an 80 upward inclination rearwardly so as to raise the rear end of the conveyor a sufficient height to permit it to discharge into a supplementary conveyor, as will be described. The bearing plate 114 is continued rearwardly to form a ring 121, as shown in Figs. 6, 10 and 11. The ring 121 receives a downwardly extending bearing ring 122 attached to the forward end of a supplemental conveyor 123. This supplemental conveyor 123 90 is provided with a hopper shaped wall 124, which is in position to be in delivery communication with the rear or discharge end of the conveyor 103, as shown in Fig. 2. The conveyor 123 is free to rotate horizontally 95 within the ring 121 to various angular positions relative to the base plate or stationary pan 20, and is supported in its various positions at its discharge end on a flange 125 carried at the rear end of the 100 base plate 20, as shown in Fig. 2. The rear loading conveyor 123 is provided with an endless flight conveyor 126 of the chain and scraper type, which is driven by a motor 127 supported by a bracket 128 secured to the 105 under side of the conveyor, as shown in Fig. 7. The motor 127 is adapted to drive a shaft 129 (Fig. 7) through gearing 130 carrying sprocket wheels 131, which engage the conveyor chains to drive the same. 110

Carried at the rear end of the conveyor bed 103 in a position directly over the supporting plate 114 is a sprocket wheel 132, as shown in Figs. 5 and 11. The sprocket wheel 132 is provided with internal gear 115 teeth 133. The points of the teeth 133 bear on the outer periphery of a circular flange 134, which extends upwardly from the upper surface of the rear portion of the bed plate 103. In this way, the circular flange 134 120 forms a journal about which the sprocket wheel 132 rotates. The sprocket wheel is driven by a pinion 135 carried on an upright shaft 136, which has its lower end journaled in a bearing 137 formed in the rear portion of the bed plate 103. The upper end of the shaft 136 is journaled at 138 in a casting 139 supported at the rear portion of the conveyor bed plate 103 by cap screws 125 which enter threaded openings 140 (Fig. 11) 130

in the plate 103. The shaft 136 is driven by a worm wheel 141, which meshes with a worm 142 driven by an electric motor 143 which is mounted on the upper portion of the casting 139. It should be understood that this casting 139 is mounted on and secured to the rear portion of the bed plate 103 so as to move bodily therewith, and therefore the mechanism for driving the chain 100 will always be in proper relative position. A casing 144 incloses the worm and worm wheel.

The conveyor chain 100 passes around a sprocket wheel 132 and is driven thereby by means of the teeth 145 carried on the outer periphery of the sprocket wheel. The motor 143 for driving the conveyor chain through the mechanism described is governed by one of the controllers 41, shown in Fig. 1. These controllers 41 are secured to the guard wall or plate 113, which guard wall also carries a foot-board or platform 146 on which the operator may stand.

As shown in Fig. 2, the casting 139 which carries the electric motor 143 has a forwardly projecting portion 150, which carries a second electric motor 151 and a bearing 152, in which is journaled one end of a threaded shaft 153. This shaft 153 has secured thereto a worm wheel 154, as shown in Fig. 5. This worm wheel 154 meshes with a worm 155 which is driven by the electric motor 151. A second bearing 156 is provided for the shaft 153 on that side of the worm wheel 154 opposite the bearing 152. In this way the shaft 153 is held against moving longitudinally relative to the conveyor bed plate 103, but is journaled for rotation in the bearings 152 and 156. The shaft 153 is threaded as shown in Fig. 5 through the standard 24 supported on the extension 23 of the base plate 20. When the electric motor 151 is driven the shaft 153 is rotated in its threaded engagement with the standard 24 and thus the conveyor bed plate 103 and the forward arcuate platform 116 are caused to slide longitudinally relative to the main frame of the machine, the direction of movement of the platform 116 being controlled by the direction of rotation of the electric motor 151, which in turn is governed by one of the controllers 41.

The main base plate 20, as shown in Figs. 2, 4, 6 and 9, is provided with an electric motor 160 for positioning the machine in the mine chamber. The electric motor 160 is connected through gearing 161 with a shaft 162, which carries a pair of drums 163, on which are wound cables 164 secured at their outer or free ends to anchors 165, which may be roof jacks or any other anchorage fastened in a suitable manner in the mine chamber. The cables 164 are each provided with a pair of guide pulleys 166 at the lateral edges of the bed plate 20 so that the

cables may be conducted in either direction from the machine frame to enable the latter to be moved into and out of the mine chamber. For instance, when roof jacks are used as anchorages at 165 and ropes 164 are arranged as shown in Fig. 2, the operation of the drums 163 to exert pulls on the cables 164 will move the whole machine forwardly approximately in the direction of the length of the machine. By locating the anchorages 165 rearwardly of the machine the latter may be drawn away from the mine wall by operation of the drums 163. The whole machine may also be shifted laterally by exerting a pull on one cable while paying out the other one, or by exerting a pull on one cable while the free end of the other remains disconnected from the anchorage.

In operation, the gathering mechanism comprising the platform 116 may be in a retracted position while the coal is being dislodged from an upright working face in advance of the machine and between the approximately parallel side walls. After the coal has been dislodged either by the machine mounted on the frame as shown in the drawings or by means of a separate machine or by means of blasting or otherwise, the electric motor 151 may be operated to rotate the threaded shaft 153 in the standard 24 so as to force the beveled nose piece 117 under the dislodged material. As the platform 116 is moved forwardly the conveyor chain 100 will be driven by the electric motor 143 and the dislodged material will be carried backwardly over the bed plate 103 and discharged into the hopper 124, which in turn directs the material on to the conveyor 126, which transfers the material to the rear end of the loading conveyor into a mine car.

During the forward sliding movement of the nose piece 116 along the mine floor the resistance due to the friction may be reduced to a minimum by using the shoes 115 shown in bottom plan view in Fig. 10 and in elevation in Fig. 5 to sustain the greater part of the weight of the forward end of the conveyor bed plate 103. It should be understood, however, that the bottom of the nose piece 116 should remain close to the floor so that the beveled edge 117 may act as a chisel to scrape up the discharged material and so that the wedging action of the beveled edge will hold the gathering mechanism at the floor so that this gathering mechanism will not ride up on the dislodged coal. Therefore, while the spaced apart shoes 115 sustain the greater portion of the weight and reduce friction, the bottom of the nose portion 116 and the forward beveled edge 117 are kept close to the mine floor so as to more efficiently scoop up the dislodged coal to be acted on by the traveling conveyor flights 101.

It should also be understood that while

the nose portion 116 is being moved forward and the beveled edge 117 is being forced under the dislodged coal, the main frame 20 is being held stationary and for this purpose, if desired, the ropes 164 may be connected to the anchorages 165 as shown in Fig. 2 and the drums 163 locked against rotation, or if desired the roof jacks 165 may be placed near the parallel edges of the base plate 20 but rearwardly thereof so as to act as abutments and prevent the base frame 20 from being moved rearwardly when the gathering mechanism is moved forwardly under the dislodged coal at the working face.

After the dislodged coal at the working face has been removed by operation of the gathering mechanism it may again be retracted so as to afford sufficient room for another series of dislodging operations at the working face. If such a mining machine as that illustrated in Fig. 5 is used the platform 116 may be moved forwardly to gather a load while another cutting operation is being carried on across the mine wall, and even during such operation the coal as dislodged may be automatically transferred to the rear loading conveyor. However, if desired the gathering mechanism may be retracted after each loading operation and moved forward only after a complete cutting operation across the mine wall has been completed. Either method of operation may be employed, and the cutting operation may be repeated as many times as is necessary to work the entire thickness of the mine vein. Whenever desired the whole machine may be moved forward to occupy a new position where the gathering mechanism may reach forward for loading purposes.

It should also be noted that while the spaced apart shoes 115 are useful to reduce friction of movement of the bottom portion of the nose piece over the mine floor, the greater portion of the conveyor mechanism is sustained by the surface 22 shown in Fig. 9. The surface 114 shown in bottom plan view in Fig. 10 and in sectional elevation in Fig. 5 is the portion which engages the surface 22.

The conveyor bed frame 103 is provided with guides 110, which span the uprights 112 and 113 of Fig. 8. Therefore, the conveyor frame 103 receives further support along the guideways 111. The base frame 20 and the standard 24 mounted on the forward end thereof remain stationary during the operation of the gathering mechanism, and so also the operator's platform 146 which is connected to the base frame 20, as shown in Fig. 8. The mechanism for thrusting the nose piece forward into the coal is operated by the electric motor 151. A separate electric motor 143 is employed for driving the flights 101, and a third separate electric

motor 127 is used for driving the rear loading conveyor 126. This is the preferred arrangement because it may be desired to move the nose piece under the coal to be loaded at a slow rate of speed while the conveyor flights are being operated rapidly. Where the coal is comparatively loose, however, the nose portion may be thrust into the coal rapidly and the conveyor flights operated at such speed as may be desirable. A separate electric motor 160 is also employed for shifting the machine forwardly or rearwardly or laterally. It will also be noted that when the mining mechanism is used one motor 35 may be employed for adjusting the elevation of the cutting mechanism and a separate motor 49 employed for operating the cutting mechanism. It will also be seen that since the hopper 124 is connected to the ring 121 shown in Fig. 11, the rear conveyor is moved forward and rearward bodily whenever the gathering mechanism is moved forwardly or rearwardly relatively to the base frame 20.

Inasmuch as the motor 143 for driving the conveyor flights 101 is an electric motor it may be reversed so that whenever there is any tendency of the material being choked while it is being moved between the walls 106, 107, the conveyor flights may be retracted so as to relieve such choking condition. Furthermore, cuttings may be loaded by the flights traveling along rearwardly under the plate 109 toward the hopper 124. As shown in Fig. 2, whether the line of draft is under the plate 109 toward the hopper 124 or along the trough at the other side toward the hopper 124, either line of draft opens directly into the hopper 124. This is evident from the manner in which the flights 101 project rearwardly beyond the rear edge of the plate 103 as shown in Fig. 2.

It will also be seen by referring to the accompanying drawings that the going and return sections of the gathering conveyor are at the same elevation. The forward conveyor is both a gathering and elevating conveyor comprising non-traveling runways and the reversible transmission belt 100 having spaced flights 101 traveling over said runways for conveying material from a runway in the forward run of the belt. In other words, the pan or bed plate 103 comprises non-traveling conveyor flight planes at the opposite runs of the belt 100. By reason of the reversibility of the electric motor 143 the chain or belt 100 is a reversible transmission belt having spaced flights traveling over the said planes or ways. The flights 101 sweep in horizontal arcs at the opposite ends of the ways and these ways at their discharge ends, as shown in Fig. 2, provide a free reverse sweep from one way to the second. The hopper 124 is provided with flaring walls and is disposed beneath the dis-

charge end of the forward conveyor and is open in the line of draft of such forward conveyor. In fact, the reversible traveling conveyor flights traverse the ways along the bed plate 103 and sweep in a horizontal arc at the opposite ends of the ways, the ways at their discharge end terminating to provide for a free flight sweep from one way to the second. ing the material on either of said planes in an advancing draft direction, a hopper beneath the discharging ends of said planes for centralizing the discharge from said planes, said hopper being open in the line of draft, a delivery conveyor leading out of and providing the base of said hopper comprising a stationary plane, the forward end providing the base of the hopper, belt trans-

It should also be noted that the rear conveyor comprises a draft line way and traveling conveyor flights traversing such way and horizontally about the opposite ends thereof. That is to say, while the gathering conveyor comprises duplex ways the delivery conveyor comprises a single way leading out of and providing a base for the hopper. The delivery conveyor comprises a way composed of a non-traveling plane. The delivery conveyor also comprises belt transmission means and spaced flights traveling over said plane on the forward run of the belt means. Since the main frame 20 is portable and shiftable to various adjusted positions by means of the rope haulage mechanism shown in Fig. 2, the drawings show mobile means for supporting and transporting the conveyors and hopper as a unit, in feeding and transit capacities. That is to say, the worm gear 154, 155 is connected with the screw-threaded shaft 153 and the standard 24 may be relied on to hold the gathering conveyor in locked position relative to the main frame. Then when the ropes 164 are anchored as shown in Fig. 2 and the drums 163 rotated the entire machine may be forced forwardly so as to move the beveled edge 117 with considerable force under the semi-mission means having spaced flights traveling over said plane on the forward run of the belt means, means for pivotally connecting said conveyors, the hopper being so located with respect to the gathering conveyor that it will be in position to unobstructively receive the material discharged from the planes irrespective of the angularity of the two conveyors, and means for supporting said conveyor and hopper as a unit in feeding and transit capacities.

2. In loading apparatus, the combination with a gathering device comprising a gathering and elevating conveyor having its discharge end elevated and its receiving end movable over the floor from which the material is to be gathered, said conveyor comprising duplex ways and a reversible transmission belt carrying spaced flights, the flights traversing the ways alternately in the forward and return portions of said belt and in a horizontal arc from one way to the second at the opposite ends of said conveyor, the ways terminating at their discharge ends, a hopper disposed beneath the discharge end of said gathering conveyor to directly receive the material from said gathering conveyor irrespective of its positions of angularity and open to the line of draft of the

compact mass of dislodged material so that the latter may be loaded by operation of the traveling flight conveyor 100, 101. By referring to Fig. 2 it will also be seen that the rear delivery conveyor may be swung laterally through a wide range while the runs of the gathering conveyor are maintained in delivery communication with the hopper 124, material, a delivering conveyor having a way leading out of and providing a base for said hopper, endless transmission means carrying spaced flights traversing said way and about a horizontal axis at each of the opposite ends of said way, the discharge end of said conveyor being elevated to receive a car therebeneath into which the conveyor is adapted to centrally discharge, and means

Obviously those skilled in the art may make various changes in the details and arrangements, all for supporting said conveyor and hopper as a unit in feeding and transit capacities.

59 arrangement of parts without departing from the spirit and scope of my invention as defined by the claims hereto appended, and I wish therefore not to be restricted to the precise construction herein disclosed.

3. In loading apparatus, the combination 115 with a gathering device comprising an elevating conveyor having a reversible transmission belt having spaced arm flights extending horizontally from the belt, of flight

Having thus fully described an embodiment of my invention, what I desire to have secured by Letters Patent of the United States, is:

1. In loading apparatus, the combination with a gathering device comprising an elevating conveyor having stationary conveyor flight planes at the opposite runs of the belt and a reversible transmission belt having spaced flights traveling over said planes, the belt being reversible for alternately conveying material in opposite directions, the conveyor being mounted for movement horizontally, a hopper disposed beneath the discharge end of said gathering conveyor open in a draft line, a delivering conveyor leading out of and providing the base of said hopper, the hopper

per directing the material therein upon said delivering conveyor, said delivering conveyor comprised of a single flight way and endless transmission means, having spaced flights traveling over said way and about a horizontal axis at each of the opposite ends of said ways, and transportable means for supporting the conveyor and hopper for movement as a unit relatively thereto.

10 4. In loading apparatus, the combination with a gathering device comprising a conveyor, of a delivering conveyor mounted for relative swinging movement on an upright axis, said gathering conveyor being in delivery communication with said delivering conveyor, of a nose portion for said gathering device with beveled edges extending along the sides of such nose portion at the surface from which the material is to be loaded, means for moving said nose portion to cause said beveled edges to gather loads for said gathering conveyor, and means for driving said conveyors.

5. In a loading machine, the combination with a stationary elongated main frame adapted to extend longitudinally of a mine chamber, of a gathering device comprising a supplemental frame having a wide platform with its forward scooping edge curved in plan, means for mounting said supplemental frame on said main frame to be confined to rectilinear forward and backward movements relatively to said main frame, means for moving said platform rectilinearly beneath the material to be loaded, and a laterally traveling conveyor on said platform back of the forward scooping edge thereof for transferring dislodged material from said platform toward loading position independently of movement of said platform.

40 6. In a loading machine, the combination with a main frame adapted to occupy a stationary position, of anchoring mechanism for said main frame comprising rope gearing connected between said main frame and anchorages in the mine, a gathering device comprising a supplemental frame mounted on said main frame for rectilinear movement relatively thereto to occupy retracted and advanced positions while said main frame is held stationary, the forward end of said receiving frame being free and unobstructed and adapted to scoop up dislodged material from the mine floor in advance of said main frame, and a traveling conveyor mounted on said receiving frame to move bodily therewith and extend along the forward end portion thereof in position to receive dislodged material.

65 7. In a loading machine, the combination with a main frame, of a gathering device comprising a receiving frame adapted to occupy a retracted position relative to said main frame and an advanced position rela-

tive thereto, means on said main frame for moving said receiving frame rectilinearly and relatively to said main frame into receiving position for receiving dislodged material near the base of the mine wall, and a traveling conveyor mounted on said receiving frame to move bodily therewith and to occupy a position for removing such material.

8. In a loading machine, the combination with a main frame, of a gathering device comprising a receiving frame having a horizontal flat bottom adapted to slide over a mine floor in advance of said main frame, means mounted on said main frame for moving said receiving frame rectilinearly to a position to receive dislodged material and to retract said receiving frame away from its receiving position toward said main frame, and traveling conveyor mechanism mounted on said receiving frame in fixed relation thereto for movement bodily therewith and for transferring material toward loading position.

9. In a loading machine, the combination with a main frame, of a gathering device comprising a receiving frame adapted to occupy a retracted position relative to said main frame, a beveled scooping edge on said receiving frame, means for moving the receiving frame rectilinearly and relatively to said main frame to move said beveled edge along the mine floor in advance of said main frame to scoop up dislodged material lying on such floor, and a traveling conveyor mounted on said receiving frame to move bodily therewith and to occupy a position for removing gathered material.

10. In a loading machine, the combination with a main frame, of a gathering device comprising a receiving frame having a beveled scooping edge adapted to move over a mine floor in advance of said main frame, means on said main frame for moving said receiving frame rectilinearly and forwardly to gather material lying on the floor near the base of an upright mine wall, such moving means also retracting said receiving frame from its receiving position toward said frame, and traveling conveyor mechanism mounted on said receiving frame in fixed relation thereto for movement bodily therewith and for transferring dislodged material toward loading position.

11. In a loading machine, the combination with a main frame, of a gathering device comprising a supplemental receiving frame having a beveled edge adapted to move over a mine floor, said supplemental receiving frame being adapted to occupy a retracted position relative to said main frame, means for moving said supplemental frame rectilinearly forwardly to gather material from the floor by means of said beveled edge, and traveling conveyor mecha-

- nism mounted on said supplemental frame, tried by said base plate and extending up in fixed relation thereto for movement bodily forwardly therefrom, a gathering device com- 70
ily therewith and for transferring gathered, comprising a platform guided on said base material toward loading position. 12. In a loading machine, the combination which said standard projects, and means as-
sociation with a supporting frame, of a gathering device comprising a platform having a forward edge arcuate in plan on a radius to effect gathering movements of said plat-
form, substantially equal to half the width of the form. 75
13. In a loading machine, the combination upwardly toward the rear and having action with a base frame, of a standard ex-
-shoulder extending along the forward arc extending upwardly from said base frame, a
-arcuate end portion of said platform; a con-
-veyer on said platform in position to be frame having a longitudinal central slot
-protected by said shoulder, means for force- therein through which said standard pro-
-jects, a shaft carried by said supplemental on the floor in advance of said supporting frame and threaded through said standard, frame, and means for operating said con-
-veyer to remove the material gathered onto plemental frame, and means for rotating
-said platform. 80
14. In a loading machine, the combination and operate said gathering mechanism. 85
-tion with a stationary supporting frame, of 18. In loading apparatus, the combination
-a gathering device comprising a platform with a portable base frame, of a conveyer
-connected to said frame and having a por- mounted thereon for sliding movement rela-
-tion of the periphery thereof beveled, said tively thereto, means at the forward end of 90
-platform being movable relatively to said said conveyer in position to move over the
-frame and in advance thereof while said surface from which the material is to be
-frame remains stationary, and mechanism loaded and direct such material to said con-
-comprising a screw connected to said sta-veyer, a rear conveyer mounted on said base
-tionary frame for forcing the beveled por- frame for sliding movement relatively there-
-tion of said periphery beneath the material to with said first-named conveyer, and a
-to be loaded. 95
15. In a loading machine, the combina- hopper for maintaining delivery communica-
-tion between said conveyors for all posi-
-tion with a stationary supporting frame, of tions of said conveyers and its directing
-a gathering device comprising a platform means relative to said base frame. 100
-connected to said frame for movement rela- 19. In loading apparatus, the combination
-tively thereto in advance thereof, said plat- with a base frame, of a gathering device
-form having its forward end free and un- comprising an elevating conveyer having
-obstructed and in position to move under ways and traveling conveyer flights travers-
-the material to be loaded, a conveyer on said ing said ways and sweeping in horizontal
-platform adjacent the forward edge thereof arcs at the ends of said ways, a hopper dis-
-in position for transferring toward loading posed beneath the discharge end of said con-
-position the material as soon as gathered by- veyer open in the line of draft, a delivery
-said platform, mechanism comprising a conveyer comprising a draft line way and
-screw connected to said stationary frame for traveling conveyer flights traversing said 105
-forcing said platform together with said way and horizontally at the opposite ends
-conveyer beneath material to be loaded, and thereof, said last-named way leading out of
-a motor for operating said screw. 110
16. In a loading machine, the combina- and providing the base of said hopper, and
-tion with a stationary frame, of a gathering means on said base frame for pivotally
-device comprising a platform movably maintain- 115
-mounted on said frame and having a slide- between said first-named conveyer and said
-way extending around the forward portion hopper.
-thereof, a conveyer mounted on said plat- 20. In loading apparatus, the combination
-form to travel along said slideway, a motor with a gathering device comprising an ele-
-connected to said conveyer to operate the vating conveyer having ways and conveyer
-same, and mechanism comprising a motor flights traversing said ways and sweeping in
-connected to a screw on said stationary horizontal arcs at the opposite ends of said
-frame for forcing said platform and con- ways, a hopper disposed beneath the dis-
-veyer forwardly relatively to said frame charge end of said conveyer open in the line 120
-while said frame remains stationary to move of draft, a delivery conveyer comprising a
-said platform under material dislodged draft line way and traveling conveyer flights
-from the face of upright mine wall. traversing said way and horizontally along
17. In a loading machine, the combina- 125
-tion with a base plate, of a standard car opposite ends thereof, said last-named way
-leading out of and providing the base of 130

said hopper, mobile means for supporting and transporting said conveyers and hopper as a unit, and means for adjusting such unit along said mobile means.

- 5 21. In loading apparatus, the combination with a portable supporting frame, of a gathering device comprising a gathering and elevating conveyer, a hopper beneath the discharge end of said conveyer, a delivery conveyer connected to said hopper and pivotally mounted to swing laterally while delivery communication is maintained between said conveyers at said hopper, and means for supporting said conveyers and hopper for 10 adjustment as a unit along said supporting frame.

22. In a loading machine, the combination with a supporting frame, of a conveyor mounted on said frame, a plate extending 20 over one run of said conveyor and adapted to serve as a step to support an operator, an additional platform elevated above said plate and adapted to support the operator, means comprising a motor for operating 25 said conveyor, and mechanism comprising a controlling lever within reach of the operator on said additional platform for controlling the operation of said conveyor.

23. In a loading machine, the combination 30 with a supporting frame, of a conveyor thereon with its opposite runs in the same

plane, a cover plate extending over the return run of the conveyor and serving as a step for the operator, an elevated platform near said plate and adapted to support an 35 operator, means for operating said conveyor, and mechanism within reach of the operator on said platform for controlling said conveyor-operating means.

24. In loading apparatus, the combination 40 with a main frame, of a gathering device comprising a supplemental frame mounted thereon for rectilinear movement relatively thereto, gathering mechanism comprising a scooping plate at the forward end of said 45 supplemental frame, means comprising a motor for operating said gathering mechanism by moving the same rectilinearly relatively to said main frame, a traveling conveyor on said supplemental frame in position to receive the gathered material and transfer the same toward loading position, 50 means comprising a separate motor for operating said conveyor, and means for controlling said motors to secure the operation of 55 said conveyor independently of the operation of said gathering mechanism.

In testimony whereof I have signed my name to this specification on this 5th day of April, A. D. 1923.

EDMUND C. MORGAN.
